UNITED STATES PATENT OFFICE.

EDWIN F. RICHARDSON, OF GREENVILLE, PENNSYLVANIA.

AIR-BRAKE VALVE.

SPECIFICATION forming part of Letters Patent No. 783,734, dated February 28, 1905.

Application filed May 26, 1904. Serial No. 209,836.

To all whom it may concern:

Be it known that I, EDWIN F. RICHARDSON, of Greenville, Mercer county, Pennsylvania, have invented a new and useful Air-Brake Valve, of which the following is a full, clear, and exact description, reference being had to the accompanying drawings, forming part of this specification, in which—

Figure 1 shows in vertical section a triple-valve mechanism provided with my device. Fig. 2 is a sectional view, on a larger scale, showing a part. Fig. 3 is a bottom plan view of the upper part of triple-valve mechanism, taken as if in section on the line III—III. Fig. 4 is a bottom plan view of the part shown in Fig. 2. Fig. 5 is a horizontal section of the engineer's brake-valve provided with my improvement and shown in running position, and Figs. 6 and 7 are respectively a side elevation and a plan view of the block B as shown in Fig. 5.

In air-brake mechanism heretofore employed in practice it has not been possible to recharge the auxiliary reservoirs with air without first releasing the brakes, and although attempts have been made to overcome this difficulty, which has limited the usefulness of air-brake valves, so far as I know none of them have heretofore been capable of successful practical use, for the reason that they involve complication of the apparatus or interfere with the normal operation of the air-brake mechanism.

My invention provides a device which will efficiently accomplish this purpose without making necessary any change in the valve mechanism of the air-brake and without in any way impairing or diminishing its efficiency.

In the drawings, in which I show the preferable form of my invention when applied to use in connection with a triple valve of known construction, 2 represents the ordinary engineer's brake-valve, which is shown in running position. The only addition which I find it desirable to make to such engineer's valve is to provide means for constricting the passage to the train-pipe when my improvement is applied to the operation of short trains, and for this purpose I prefer to set in the train-

pipe passage 3 a valve-plug 4, which may be turned so as to expose a large port 5 when it is not desired to constrict the passage 3 or to present a smaller port 6 when a constricted opening is desired for the purpose of limiting the volume of air passing to the train-pipe, as is desirable in the operation of my improvement with short trains.

7 is the connection of the train-pipe to the triple valve.

8 is the triple-valve piston, and 9 the piston-head, which when in the released position (shown in Fig. 1) opens a port 10 and affords communication by way of a passage 11 between the train-pipe and the auxiliary reservoir, the connection on which is indicated at 12. When the pressure is exhausted from the train-pipe as in the ordinary operation of the valve, the piston-head 9 moves to the left in Fig. 1, and thus closes the port 10, cutting off communication between the train-pipe and the auxiliary reservoir and establishing connection between the auxiliary reservoir and the brake-cylinder for the purpose of setting the brakes, and it has heretofore in practice not been possible to reestablish the connection between the train-pipe and the auxiliary reservoir without again opening the port 10 by moving the valve-piston, and thus releasing the brakes. My invention makes it possible to establish this communication between the train-pipe and the auxiliary reservoir without moving the valve-piston to released position.

For this purpose I employ a by-pass 13, which leads to the space back of the piston-head 9 of the triple valve and communicates at its lower end, through a port 14, with the passage 11 or with the train-pipe and has an automatically-acting check-valve 15, preferably made in the form of a steel ball, which is set in an enlarged portion 16 of the by-pass and is confined therein by a tapped plug 17. The end of this plug 17 and the opposite end of the chamber 16 are rounded, so as to afford seats for the valve 15. This valve normally rests by gravity on the lower seat and cuts off communication between the by-pass and the train-pipe.

In the operation of the air-brake system if the engineer should desire to recharge the

auxiliary reservoir without releasing the brakes he moves the handle of the engineer's valve from service position to running position. This motion connects the train-pipe 5 with the source of air at the engine and admits a limited supply of compressed air to the train-pipe. The pressure of this limited supply of air acting upon the valve 15 is sufficient to raise this valve from its lower 10 seat and to permit the discharge of air through the by-pass and through the chamber of the piston 8 to the auxiliary reservoir, but is not sufficient to move the piston-head 9 far enough to open the port 10. To accomplish this re- 15 sult, the weight of the valve 15 is made such that it will oppose less resistance to the air than the friction of the valve-piston 8 within its chamber. In this way communication is established between the air-pressure in the 20 train-pipe and the auxiliary reservoir without moving the valve-piston 8 to released position, and therefore without releasing the brakes. If, however, the engineer should desire to release the brakes, he will move the 25 handle of the engineer's valve to full release position, thereby admitting the full pressure of the air to the train-pipe. This pressure is sufficient not only to unseat the valve 15 from its lower seat, but to force it against its upper 30 seat, thus closing the by-pass 13 and causing the full pressure of the train-pipe to be exerted upon the piston-head 9, thus moving the piston to the released position (shown in Fig. 1) and opening the port 10.

35 The triple valves ordinarily employed have a graduating device in which the piston of the triple valve is provided with an independently-movable graduating-valve rendered capable of a short preliminary motion sufficient 40 to cut off communication between the auxiliary reservoir and the brake-cylinder without moving the triple-valve piston itself. The motion of this graduating-valve is effected by moving the handle of the engineer's valve 45 from service position to lap position. This is not affected or changed by the use of my improvement, for by having the check-valve 15 of such weight that it will oppose greater resistance to the air-pressure than the packing- 50 ring of the graduating-valve on the triple-

valve piston the graduating-valve will be moved by bringing the engineer's valve to lap position without moving the check-valve 15, and therefore without admitting the pressure through the by-pass to the auxiliary reservoir. 55

Within the scope of my invention persons skilled in the art will be able to change the construction in many ways, both as to the construction and location of the by-pass and its valve and in other particulars, for the purpose of adapting it to different types of triple valve. All such modifications I intend to cover in my claims, since

What I claim is—

1. Means for recharging an auxiliary reservoir without releasing the brakes, comprising in combination with a triple valve, auxiliary reservoir and train-pipe, a valved, recharging by-pass back of the triple-valve piston-head, and means for automatically opening said by-pass on the application thereto of pressure less than required to move the triple valve to released position; substantially as described. 65

2. Means for recharging an auxiliary reservoir without releasing the brakes, comprising in combination with a triple valve and its graduating-valve, the auxiliary reservoir and train-pipe, a valved, recharging by-pass in rear of the triple-valve piston, and means for automatically opening said by-pass on the application thereto of pressure less than required to move the triple valve to released position and somewhat greater than that required to move the graduating-valve; substantially as described. 70

3. Means for recharging an auxiliary reservoir without releasing the brakes, comprising an auxiliary reservoir, a train-pipe, a triple valve having a by-pass in rear of the piston 90 thereof, and a valve in said by-pass adapted to seat at either end of its travel; substantially as described.

In testimony whereof I have hereunto set my hand.

EDWIN F. RICHARDSON.
